WOLFGANG E. SCHWARZMANN, OF LONGMEADOW, AND ADOLPH ROSNER, OF SPRINGFIELD, MASSACHUSETTS, ASSIGNEES TO AMERICAN BOSCH MAGNETO CORPORATION, OF SPRINGFIELD, MASSACHUSETTS, A CORPORATION OF NEW YORK.

TIMER DISTRIBUTOR.

Application filed June 4, 1921. Serial No. 475,063.

To all whom it may concern:

Be it known that WOLFGANG E. SCHWARZMANN and ADOLPH ROSNER, citizens of the United States, residing at and whose post office addresses are, respectively, 51 Belleclaire Avenue, Longmeadow, and 4 Ventura Street, Springfield, in the county of Hampden and State of Massachusetts, have invented certain new and useful Improvements in Timer Distributors; and we do hereby declare the following to be a full, clear, and exact description of the invention, such as will enable others skilled in the art to which it appertains, to make and use the same.

15 The present invention relates to timer-distributors for electric ignition systems for internal combustion engines.

Owing to the small size of the interrupter mechanism and the high speed at which it must operate at times, it is necessary that the relation of the parts of the interrupter mechanism be maintained constant even to minute dimensions. For instance, the normal opening of the interrupter contacts is often one hundredth of an inch or even less, and that opening is usually brought about by a cam acting on a bumper block carried by the deflecting lever between the contact point and the pivot thereof. Hence, it is evident that the relation of the cam and interrupter lever must not only be set with exactitude but must be maintained so.

Heretofore, it was customary to mount the interrupter on an integral part of the housing or else on a plate disengageably fastened to the housing. In such forms of construction, either the interrupter mechanism could not be removed from the housing for inspection, adjustment and repair, or where removable, the plate did not assure the exactitude required in the setting and the maintenance thereof, due to the possible tilting of the interrupter mechanism on its supporting member.

45 In accordance with our invention, the interrupter mechanism is removable, its exact relocation and maintained relation with respect to the interrupter cam being assured by mounting the interrupter mechanism in a cup which has its upstanding peripheral flange closely fitting in a supporting member with such flange coacting with such member to center the cup around the driving

shaft of the interrupter, thereby exactly locating it and precluding the possibility 55 of its tilting. If desired, the cup may have means, such as pressed out seats at the lower corners of the cup coacting with a shelf in the supporting member to locate the cup axially of the shaft, and thereby assist 60 in preventing disalignment and tilting.

In order that the interrupter mechanism may be conveniently inspected when removed without electrically disconnecting it, the electrical connections, which may be in the form of binding posts, are carried by the cup, preferably by the upstanding flange thereof, open slots being provided, if desired, in the upper part of the supporting member for the passage of such connections to the exterior and for the sliding thereof into and out of such slots. The cup housing the interrupter mechanism, the supporting member therefor, which may or may not house automatic advance governing mechanism but in either event housing the driving shaft, and the distributor cup housing the distributor mechanism, form together a three part housing which co-act 75 to locate and maintain the parts in exact 80 relationship.

Our invention also comprehends as another of its parts, a provision of cooperative means, such as a radial projection on the cup flange extending into a slot in the supporting member, for preventing the relative turning or angular movement thereof. This may be accomplished by so locating the electrical connections or binding posts and the open slots in the supporting member, that the former will be replaceable in the latter in but a single angular relation. Moreover, whether or not automatic timing mechanism be used, the ignition advance may be effected manually by angular movements of the interrupter mechanism relative to its actuating cam. By thus providing means for assuring and maintaining a fixed angular relation between the cup and the supporting member, the latter may be manually angularly moved 100 for this purpose.

For the purpose of venting any gases formed internally, our invention comprehends as another of its parts, the provision of vent openings in the cup and in the supporting member, with the openings of the

cup registering with those in the member. The openings in the supporting member may be formed by providing hollow rivets fastened in the side wall of the supporting member and registering with the openings formed in the flange of the cup. These rivets may also fasten to the supporting member, the spring clips, which coact with the distributor cap to hold it axially engaged with the supporting member.

In the accompanying drawing, illustrating two embodiments of the invention, with and without an automatic governor mechanism;

Fig. 1 is a view in side elevation of one form of device constructed in accordance with our invention; Fig. 2 is a similar view of the parts shown separated for the purpose of clearness; Fig. 3 is a fragmentary sectional view taken on line 3-3 of Fig. 1; Fig. 4 is a bottom view of the removable housing cup for the interrupter mechanism; Fig. 5 is a fragmentary sectional view taken on line 5-5 of Fig. 4; and Fig. 6 is a view similar to Fig. 1 of another form of the invention, omitting the governor mechanism. Referring more particularly to the drawing, the invention is illustrated as comprising a supporting member or governor housing 1, an interrupter housing cup 2 and a distributor cap 3, with the cup 2 removably inserted within the upper open end of the housing 1 and the cap 3 detachably mounted upon the upper flanged end of the governor housing 1. The latter is provided with a depending portion 4 and an inwardly extending portion 5 acting as a bearing for the driving shaft 6 driven by a moving part of an engine or generator through a pinion 7 fixed to the shaft 6, for driving a governor mechanism 8 located in the housing 1, an interrupter cam 9 included within the cup 2, and a distributor rotor 10 included within the chamber of the distributor cap 3, the interrupter cam 9 and the distributor rotor 10 being automatically advanced or retarded by the governor mechanism 8 during the rotation of the shaft 6, depending upon the rate of rotation of such shaft. The lower portion of the housing 1 also is connected to a timing lever 11 by which the housing 1, cup 2 and cap 3, as well as the parts carried thereby, may be manually and angularly moved, in order to manually control the advance or retard of the ignition.

Within the cup 2 is included a suitable interrupter mechanism which, with the exception of the interrupter cam 9 forming part of the shaft 6, is supported upon the base or bottom 12 of the cup 2. This mechanism comprises an interrupter lever 13, of sheet metal and of channel shape in cross-section, suitably pivotally mounted on the bottom 12, and carrying a fibre contact piece 14 or block 14 with which engages the cam 9.

The lever 13 with its contact block 14 is constantly held in engagement with the cam 9 by a pair of springs 15 connected at one end to the lever 13 and reacting at the other end against a block 16 forming part of a screw 70 stud 17 extending radially outwardly through openings 18 and 19 in the sides of the cup 2 and housing 1, respectively. Within the opening 19 is inserted a socket member 20, of insulating material, which is apertured to receive the screw threaded end of the stud 17 and also recessed on its inner side to receive a rectangular enlargement 21 on the stud 17, such enlargement preventing the turning of the stud 17 when once positioned. Between the part 21 and the block 16 is interposed a bifurcated end of a spring 22 which conducts current from the stud 17 to the interrupter lever 13. An insulating piece 23 is interposed between the block 16 and the side of the cup 2, and a portion 24 of the insert or socket member 20, extends through the opening 18 into contact with the insulating piece 23 for the purpose of insulating the stud parts from the cup 2. The outer end of the socket member 20 is recessed to receive lock nuts 25, the forked end of the primary lead terminal and the shank 26 of a thumb nut or button 27 threaded to the stud 17, the terminal of the primary lead being bound between the nuts 25 and the shank 26. The lever 13 carries the usual contact element adapted to engage with and separate from a relatively stationary contact, and is also connected to a condenser 28 enclosed in a casing 29 located in the cup 2 on the opposite side of the shaft 6 from the interrupter lever, one terminal of the condenser being grounded through the casing 29 and the base plate 12 of the interrupter cup 2.

To the cup 2 is secured, on the upwardly extending peripheral flange thereof, a radially extending binding screw stud 30 which is adapted to slide and fit into, as well as extend through, an open slot 31 formed in the upper flanged portion of the governor housing 1. The part of the housing 1, where the slot 31 is formed, is thickened or provided with a boss 32 which has a recess 33 in which is placed a washer 34 between which and a binding nut 35 threaded upon the outer end of the screw stud 30, may be secured the terminal of a ground lead. The screw stud 30, aside from serving the purpose of a binding post also acts or serves, when inserting the cup in the upper end of the governor housing and sliding the screw 30 into the slot 31, as a positioning lug, thus assuring a correct positioning of the housing cup 2, together with the interrupter mechanism, in angular respect to the governor housing. The locating of the screw stud 30 in the slot 31 further serves to maintain the housing cup 2 in fixed angular relation with

respect to the governor housing, thus preventing rotation of the former upon and relative to the latter.

Within the chamber of the housing 1 is provided an oil well 36 which contains a quantity of oil or other lubricant adapted, during the operation of the governor mechanism, to be splashed about within the chamber of the casing 1, so as to constantly and automatically lubricate the various parts of the governor mechanism. The shaft 6, however, is provided with an oil deflecting ring or collar 37 at the upper portion of the chamber, adapted, during the rotation of the shaft, to centrifugally cast off or deflect an oil that may have worked its way upwardly along the shaft or splashed upwardly within the governor housing so as to guard against the access into the interior of the cup 38 through the opening 38 provided in the lower wall 12 of the cup.

Upon the outside of the housing 1 may be suitably attached a name plate 39, in the form of a band, secured to the housing by means of escutcheon pins 40, if desired. At the upper end of the governor housing 1 are provided, on the opposite sides thereof, bosses 41 through which extend hollow rivets or eyelets 42, between the outer flanges of which and the bosses 41 are secured pivot straps or hinge members 43. The lower ends of the latter are curved to provide bearings or seats for pivot pins 44 upon which are pivotally mounted spring clips 45, the upper hooked end portions 46 of which are adapted to clasp with the distributor cap 3 upon the shoulders 47 thereof, the spring clips thus acting to retain the housing 1, cup 2 and the distributor cap 3 in assembled relation. The hollow rivets 42 serve a double function of securing the pivot straps 43 to the sides of the housing 1 and to also permit the entry of air for air circulation within the interior of the device and the venting of foul gases therefrom, the cup 2 being provided with suitable apertures 48 located in register with the passages of the rivets 42, as is clearly shown in Fig. 1 of the drawing.

It will be apparent that the cup is constructed so as to rest or fit within the upper end portion of the supporting member or housing 1, and is readily detachable therefrom so as to permit ready inspection of the interrupter mechanism. By having a complete interrupter mechanism within a detachable housing or cup so that the whole device may be detached and yet be capable of being inspected and tested, is a new feature and is part of our invention. The cup is preferably formed by drawing it from a piece of sheet metal into the form shown in Fig. 2 and of a diameter to slidably and snugly fit in the upper open end of the housing 1. The cup will accordingly have its

lower edge or corner 50 somewhat rounded. This corner may, if desired, seat upon a shelf or shoulder 51 formed within the housing 1, but we preferably form on the cup, a number of seats 52 by pressing out, at desired points, along the lower edge or corner 50, portions thereof to form such seats. This is accomplished by means of suitable tools, such as a punch and die, the former being applied internally of the cup to force a portion of the metal thereof outwardly against a die, of suitable shape, applied exteriorly of the cup at the desired point opposite the point of application of the tool. The displacement of the metal by the punch is shown by the recess 53. In placing the cup in the housing 1, the seats 52 will sit squarely on the shelf 51 thus limiting the inner movement of the cup. It will be noted that these seats are located at the outermost points of the cup, so that any possible slight variation in position in their coaction with the shelf, will not be appreciable at the central region of the cup where the interrupter cam 9 and block 14 operate. In this way the possibility of the cup tilting with respect to the axis of the shaft 6 is precluded. This is also aided by the height of the peripheral flange of the cup which by reason of its close fit within the open end of the housing 1 further prevents tilting action of the cup.

On the distributor cap 3 is provided a depending lug 49 adapted, when mounted in proper position, to extend into the upper end of the slot 31, whereby the cap 3 will be locked in proper angular relation with respect to the housing 1 and cup 2. Inasmuch as the screw 30, lug 49 and slot 31 are provided on merely one side of the device, it is impossible to connect the parts together at 180° from the correct position, but it is only possible to connect the parts together in one relation of the parts. The cap 3 also comprises a circular series of lead posts 54 with in each of which is located a terminal insert 55 having a lower terminal portion 56 coactive with the end 57 of a rotor insert 58 suitably secured to the rotor 10, as is clearly shown in Fig. 3. It will be observed that the peripheral flange of the cup projects upwardly beyond the end of the housing 1 and thus fits into and coacts with the lower rim of the distributor cap 3, so as to center the cap, and the terminals carried by it, in correct relation with the rotor insert. The cap also has a high tension lead center post 59 within the lower end of which is located a contact brush 60 in rubbing contact with the insert 58.

In Fig. 6 we have shown another form of device, constructed in accordance with the invention, identical in structure with that shown in Figs. 1 to 5 inclusive, with the exception that no governor mechanism is used, and accordingly, the supporting mem-

ber or housing 61 is of shorter length than the supporting member or housing 1. The features of invention above described are also applicable to a timer-distributor having no governor mechanism.

Having thus described our invention what we claim is:

1. In a timer-distributor having an interrupter mechanism, a distributing mechanism and a driving shaft therefor, the combination of a three part housing comprising a supporting member housing the driving shaft and having a bearing therefor, a cup housing the interrupter and being removably supported in said member, and a distributor cap housing the distributing mechanism and being detachably fastened to said member, said cup having an upstanding peripheral flange coacting with said member to center said cup around the shaft, and having means coacting with a continuous shelf in said member to locate said cup axially of the shaft.
2. In a timer-distributor having an interrupter mechanism, a distributing mechanism and a driving shaft therefor, the combination of a three part housing comprising a supporting member housing the driving shaft and having a bearing therefor, a cup having an upstanding peripheral flange housing the interrupter mechanism and being removably supported in said member, a distributor cap housing the distributing mechanism and being detachably fastened to said member; and electrical connections for said interrupter mechanism carried by said flange.

3. In a timer-distributor having an interrupter mechanism, a distributing mechanism and a driving shaft therefor, the combination of a three part housing comprising a supporting member housing the driving shaft and having a bearing therefor, a cup having an upstanding peripheral flange housing the interrupter mechanism and being removably supported in said member, a distributor cap housing the distributing mechanism and being detachably fastened to said member, and electrical connections for said interrupter mechanism carried by said flange, said member having open slots for the passage of said connections to the exterior thereof.

4. In a timer-distributor having an interrupter mechanism, a distributing mechanism and a driving shaft therefor, the combination of a three part housing comprising a supporting member housing the driving shaft and having a bearing therefor, a cup having an upstanding peripheral flange housing the distributor mechanism and being removably supported in said member, a distributor cap housing the distributing mechanism and being detachably fastened to said member, and binding posts for the

interrupter mechanism carried by said flange and extending exteriorly of said member for connection of leads thereto.

5. In a timer distributor having an interrupter mechanism, a distributing mechanism and a driving shaft therefor, the combination of a three part housing comprising a supporting member housing the driving shaft and having a bearing therefor, a cup having an upstanding peripheral flange housing the distributor mechanism and being removably supported in said member, a distributor cap housing the distributing mechanism and being detachably fastened to said member, and binding posts for the interrupter mechanism carried by said flange and extending exteriorly of said member for connection of leads thereto, said member having open slots for the passage of said posts therethrough.

6. In a timer-distributor having an interrupter mechanism, a distributing mechanism and a driving shaft therefor, the combination of a three part housing comprising a supporting member housing the driving shaft and having a bearing therefor, a drawn cup housing the interrupter mechanism and being removably supported in said member, and a distributor cap housing the distributing mechanism and being detachably fastened to said member, said cup having an upstanding peripheral flange coacting with said member to center said cup around the shaft and also having pressed out seats coacting with a continuous shelf in said member to locate said cup axially of said shaft.

7. In a timer-distributor having an interrupter mechanism, a distributing mechanism and a driving shaft therefor, the combination of a three part housing comprising a supporting member housing the driving shaft and having a bearing therefor, a cup housing the interrupter mechanism and being removably supported in said member, and a distributor cap housing the distributing mechanism and being detachably fastened to said member, said cup and member having registering openings for internal venting.

8. In a timer-distributor having an interrupter mechanism, a distributing mechanism and a driving shaft therefor, the combination of a three part housing comprising a supporting member housing the driving shaft and having a bearing therefor, a cup housing the interrupter mechanism and being removably supported in said member, a distributor cap housing the distributing mechanism and being detachably fastened to said member, and hollow rivets provided in the side of said member, the flange of said cup having openings in registry with said hollow rivets for internal venting.

9. In a timer-distributor having an inter-

rupter mechanism, a distributing mechanism and a driving shaft therefor, the combination of a three part housing comprising a supporting member housing the driving shaft and having a bearing therefor, a cup housing the interrupter mechanism and being removably supported in said member, a distributor cap housing the distributing mechanism and being detachably fastened to 5 said member, hollow rivets provided in the 10 side of said member, and distributor cap spring clips fastened to said member by said rivets, the flange of said cup having openings in registry with said hollow rivets for internal venting. 15

In testimony whereof we affix our signatures.

WOLFGANG E. SCHWARZMANN.
ADOLPH ROSNER.
